United States Patent Office

Des. 203,054
Patented Nov. 30, 1965

203,054

CUP

Roland W. Gregory, Commerce City, Colo.
(7531 Niagara St., Denver, Colo.)

Continuation of design application Ser. No. 69,443,
Mar. 26, 1962. This application Mar. 9, 1964, Ser. No.
79,163

Term of patent 14 years

(Cl. D44—9)

FIG. 1.

FIG. 4.

FIG. 3.

FIG. 2.

FIG. 1 is a perspective view, taken from the left side, of a cup showing my new design;

FIG. 2 is a rear perspective view thereof;

FIG. 3 is a front perspective view thereof; and

FIG. 4 is a perspective view, taken from the right side, of a cup similar to the cup of FIG. 1, but with the handle reversed in position.

This application is a continuation of my earlier filed application Serial No. D-69,443 filed March 26, 1962, now abandoned.

I claim:

The ornamental design for a cup, as shown and described.
